UNITED STATES PATENT OFFICE.

DAVID J. SEAMAN, OF SOUTH BEND, INDIANA.

DESIGN FOR FABRIC.

SPECIFICATION forming part of Design No. 34,427, dated April 23, 1901.

Application filed April 1, 1901. Serial No. 53,977. Term of patent 14 years.

To all whom it may concern:

Be it known that I, DAVID J. SEAMAN, a citizen of the United States of America, residing at South Bend, in the county of St. Joseph and State of Indiana, have invented and produced a new and original Design for Fabrics, of which the following is a specification, reference being had to the accompanying drawing, which forms a part hereof.

This design relates to the ornamentation of cotton, silk, woolen, paper, celluloid, and other fabrics.

In the drawing I have shown a plan view of my design.

The leading feature of the design is the representation of a continuous string of holly-leaves, running along or upon the surface of

the fabric, with sprays shooting therefrom at intervals. The holly-leaves A, interspersed with berries B, appear to spring from stems C, running along the fabric, and at regular intervals single stems D shoot to one side from the stems C and form distinct lateral branches or sprays.

What I claim is—

The design for a fabric herein described and shown.

In testimony whereof I have signed this specification in the presence of two attesting witnesses.

DAVID J. SEAMAN.

Witnesses:

FRANK W. BAUDE,
THOMAS J. HANLON.
